Primary Examiner — Joseph Kukella*Assistant Examiner* — Lillian Windham(57) **CLAIM**

The ornamental design for a ruler, as shown and described.

DESCRIPTION

FIG. 1 is a top, rear and right side perspective view of a ruler showing my new design;

FIG. 2 is a top, front and left side perspective view thereof; and,

FIG. 3 is a top plan view thereof.

The broken lines in the drawings illustrate portions of the ruler which form no part of the claimed design.

1 Claim, 3 Drawing Sheets Fig. 1
